SAFETY RAZOR

Frank A. Gaide, South Boston, Mass.

Application April 21, 1944, Serial No. 532,067

3 Claims. (Cl. 30—41)

This invention relates to safety razors, and the primary object of the present invention is to provide a safety razor of modernistic design and including a block-like body adapted to be employed as a handle of the razor and capable of being readily molded of plastic material.

Another object of the invention is to provide a razor of the above kind in which simple and efficient means is provided for securing a razor blade in shaving position at one end of the body.

Another object of the invention is to provide a safety razor of the above kind in which the body is formed with a recess directly behind the exposed edge portion of the razor blade for permitting rearward passage of the soap and hairs during the shaving operation, and in which the soap and hairs may collect for being readily removed by washing at the completion of the shaving operation. The present invention more specifically contemplates the provision of a safety razor of the above kind which may be readily kept in a clean and sanitary condition, and wherein simple and efficient means is provided for readily permitting removal or application of the razor blade.

Other objects and features of the present invention will become apparent from the following description when considered in connection with the accompanying drawings, and the invention consists in the novel form, combination and arrangement of parts hereinafter more fully described, shown in the drawings and claimed.

In the drawings, wherein the same reference characters indicate the same parts throughout the several views:

Figure 1 is a developed perspective view showing the various parts of the present razor separated and in relative position for assembly.

Figure 2 is a front elevational view of the assembled razor constructed as illustrated in Figure 1.

Figure 3 is a side elevational view looking upwardly at Figure 2.

Figure 4 is a rear elevational view of the razor as shown in Figure 2.

Figure 5 is a central longitudinal section taken on line 5—5 of Figure 2.

Figure 6 is a transverse section taken on line 6—6 of Figure 5.

Figure 7 is a transverse section taken on line 7—7 of Figure 5.

Figure 8 is a view partly in central longitudinal section and partly in side elevation, of a modified form of the invention.

Referring in detail to the drawings, and par-

ticularly to Figures 1 to 7, inclusive, the present safety razor includes a handle-forming body including a main outer section 5 and a removable inner end section 6. The body is of flat elongated block-like form and provided with rounded edges, as well as preferably tapering smaller or narrower from the outer to the inner end, as illustrated in Figures 2 and 4. The body sections may be conveniently molded of plastic material so that the inner portion of the main outer section 5 is formed with a central chamber 8 that opens through the inner end of said section 5 and is adapted to receive a quantity of razor blades for storing them in a conveniently accessible position. The inner end of body section 5 is preferably reduced, as at 9, the inner body section 6 being removably fitted over this reduced end so as to form a closure for the chamber 8. The body is provided with a rather blunt wide outer end, and a rabbet 10 is formed in the surface of the outer end of the body so as to extend for a greater portion of the width of said end and to provide a shoulder against which the razor blade 11 is adapted to be clamped within the rabbet 10. A slot or recess 12 is provided in the body directly outwardly of the chamber 8, and disposed with its major portion within this slot or recess is a knurled circular knob 13 having the inner end of a spindle 14 secured therein. In this embodiment of the invention, the recess or slot 12 is preferably provided in the back of the body and does not extend entirely through the latter. The body is provided with a suitable bore 15 longitudinally thereof and centrally between the sides of the same, and the inner portion of this bore is enlarged to receive the projecting forward end portion of spindle 14. This outer end of spindle 14 is provided with an axial threaded socket 16 adapted to threadedly receive the threaded free end portion 17 of a shank 18 centrally carried by and projecting inwardly from a blade-clamping plate 19. The shank 18 projects through the forward smaller portion of bore 15 and is preferably of elliptical or oval cross section for snug reception within a notch 20 provided in the back edge of the blade 11, thereby preventing turning of the blade relative to the shank 18. If desired, the clamping plate 21 may have projecting lugs on its inner face, as indicated by dotted lines in Figure 1, and the blade 11 may have slots 22 to receive these lugs when the plate 19 is in clamping position with respect to the blade. Also, the lugs 21 may enter grooves 23 provided in the wall of the rabbet 10 which forms the abutment shoulder for the blade 11.

In this way, the blade 11 and clamping plate 19 may be effectively restrained against tendency to turn about the axis of the shank 18 when the blade and clamping plate are being drawn inwardly to clamped position. The latter is effected by centering the threaded end 17 of shank 18 relative to the socket 16 of spindle 14 and then rotating the latter to thread the end 17 into socket 16 by actuation of knob 18. When in clamping position, the plate 19 is also within the rabbet 10 and snugly drawn against the blade 11. Reverse rotation of knob 18 will effect disconnection of the clamping plate 19 from spindle 14 so that the blade may be removed. However, the arrangement is preferably such that the lugs 21 disengage from the slots 22 of the blade before the threaded end 17 of shank 18 becomes detached from the spindle 14, thereby permitting removal of the blade 11 without entirely removing the clamping plate 19.

As shown clearly in Figure 5 and also indicated in Figures 1 to 3, inclusive, the front face of the body is provided at its outer end with a recess 24 that extends to the rabbet 10 so as to expose the active edge portion of the blade 11. This permits the soap and hairs to pass rearwardly into the recess 24, as shaving proceeds, and the accumulated soap and hairs may be readily washed from this recess upon completion of the shaving operation. A transverse guard bar 25 extends across the front portion of recess 24 directly behind and parallel with the cutting edge of blade 11. Obviously, this guard bar may have guard teeth if desired. As shown more clearly in Figure 2, the recess 24 gradually merges at the rear thereof with the front face of the body and extends a considerable distance rearwardly of the blade so as to have a considerable capacity and render it unnecessary to wash the soap and hairs therefrom until the completion of the shaving operation. Also, the recess 24 is of a width corresponding to the length of the rabbet 10 so as to extend for the full length of the blade 11.

While the invention has been described and illustrated in Figures 1 to 7 as embodied in a single-edge type of razor, it may be embodied in a double-edge type of razor, as generally illustrated in Figure 8. In that event, a recess 24a, similar to the recess 24, is simply provided in both flat surfaces of the body, a guard bar 25a being associated with each recess 24a. Also, the body is made slightly thinner so that a double-edge blade 11a will have its cutting edges exposed beyond the bottoms of both recesses 24a. In this embodiment, the bore 15a is provided midway between the flat surfaces of the body and receives the shank 18a of a suitable clamping plate 19a for use with the double-edge blade. Also, the spindle 14a which threadedly receives the inner end of shank 18a carries a knob 18 that has its periphery exposed at opposite sides of the body. The latter is accomplished by making the slot 12a extend through the body for the full thickness thereof, and by using a knob 18a of a diameter slightly greater than the thickness of the body. In this form, the main section of the body is indicated at 5a and its razor blade chamber at 8a, the removable inner section which forms a clo-

sure for the chamber 8a being indicated at 6a. Obviously, the front outer end of the body in Figure 8 may have a recess to receive the blade 11a and clamping plate 19a that is in the form of a groove rather than a rabbet in that it opens through both flat faces of the body. However, it is only necessary to allow the razor blade to abut the end of the body, as shown.

From the foregoing description, it is believed that the construction and operation, as well as the advantages of the present invention, will be readily understood and appreciated by those skilled in the art. Minor changes in details of construction illustrated and described are contemplated, such as fall within the spirit and scope of the invention as claimed.

What I claim is:

1. A safety razor comprising a flat elongated block-like body having rounded edges and adapted to form a handle, said body having a broad outer end providing a seat for a razor blade and being provided with a recess in its outer portion, said recess extending to the blade seat and affording a space for the rearward passage and accumulation of soap and hairs from the blade, means carried by the body for releasably securing the blade against said seat, and a transverse guard bar extending across and spaced from the bottom of said recess directly rearwardly of the blade.
2. A safety razor comprising a flat elongated block-like body having rounded edges and adapted to form a handle, said body having a broad outer end formed with a recess providing a shoulder against which a razor blade may be seated, said body further having a slot therein and a bore extending outwardly from the slot to the blade recess, a spindle journaled in the inner portion of said bore and having a knob fixed therein within said slot, said spindle having an axial threaded socket in its outer end, and a clamping plate for securing the blade in position, said clamping plate having a shank extending inwardly within the forward portion of said bore and threadedly engaged in the socket of said spindle.
3. A safety razor comprising a flat elongated block-like body having rounded edges and adapted to form a handle, said body having a broad outer end formed with a recess providing a shoulder against which a razor blade may be seated, said body further having a slot therein and a bore extending outwardly from the slot to the blade recess, a spindle journaled in the inner portion of said bore and having a knob fixed thereon within said slot, said spindle having an axial threaded socket in its outer end, and a clamping plate for securing the blade in position, said clamping plate having a shank extending inwardly within the forward portion of said bore and threadedly engaged in the socket of said spindle, said body further having a recess in the outer portion of its front surface leading rearwardly from the blade for the rearward passage and accumulation of soap and hairs from the blade, and a transverse guard bar extending across and spaced from the bottom of said recess directly behind the blade.

FRANK A. GAIDE.
